UNITED STATES PATENT OFFICE

NORMAN L. SNOW, OF NEW CANAAN, CONNECTICUT, ASSIGNOR TO DIAMOND POWER SPECIALTY CORPORATION, OF DETROIT, MICHIGAN, A CORPORATION OF MICHIGAN

BOILER CLEANER

Application filed November 26, 1923, Serial No. 677,166. Renewed January 28, 1929.

The invention relates to boiler cleaners and refers more particularly to that type having a rotatable blower element adapted to discharge steam or the like upon the boiler tubes. One of the objects of the invention is the provision of a boiler cleaner unit having a rotatable blower element and a valve controlling the passage of steam or the like to the blower element and provided with means for operating the blower element and normally operating the valve and for rendering the valve inoperative at a predetermined interval during the operation of the blower element. Specifically, the construction is such that the valve controlling the admission of steam or the like to the blower element is opened and closed during the rotation of the blower element until the latter has been rotated a predetermined number of times after which the valve remains closed. Another object is the provision of means for operating the valve, dependent upon the operation of the blower element and including means also dependent upon the operation of the blower element for controlling the operation of the valve. A further object is the provision of means for rendering the valve inoperative after a predetermined number of operations of the blower element and of means for then rendering the valve operative.

With these as well as other objects in view, the invention resides in the novel features of construction and combinations and arrangements of parts as more fully herein-after set forth.

In the drawings:

Figure 1 is a side elevation of a boiler cleaner unit embodying my invention;

Figure 2 is an end view thereof partly broken away;

Figure 3 is a top plan view thereof;

Figures 4, 5 and 6 are views corresponding to Figures 1, 2 and 3 but showing a modified construction of boiler cleaner.

In Figures 1 and 2, I have illustrated a boiler cleaner unit in which 1 is the blower element adapted to discharge steam or the like against and between the boiler tubes and 2 is the stationary gooseneck connected by

the usual swivel to the blower element. The lower end of the gooseneck has the casing 3 for the valve 4 which controls the admission of steam or the like to the blower element through the gooseneck.

The blower element is rotated in the present instance by a chain passing over the sheave 5, which latter is connected to the blower element by suitable reduction gearing such as the pinion 6 and gear 7. The valve is opened by means of the cam 8 beside and concentric with the gear 7 and rotatable therewith, the lever 9 having its upper end engageable with the cam and its lower end pivoted at 10 upon the lug 11 extending upwardly from the valve casing 3 and also the disk 12 engageable by the lever and engageable with the valve stem 13 which extends upwardly through the top of the valve casing. The disk 12 is movable axially and is held in normal position by means of the coil spring 14 surrounding the hollow stem 15 upon the disk which telescopes over the column 16 extending upwardly from the valve casing.

With the arrangement as thus far described, as the blower element 1 is rotated, the lever 9 is swung about its pivot 10, thereby depressing the disk 12, which, in turn moves the valve stem 13 longitudinally downward and thereby moves the valve 4 to open position. As the operating portion of the cam becomes disengaged from the lever, the disk 12 is moved axially upward by the coil spring 14 and the valve stem 13 is moved axially upward by means of the coil spring 17 surrounding this valve stem and abutting the packing gland 18 and the collar 19, which latter is secured to the upper end of the valve stem. Thus, for each rotation of the blower element, the valve is opened and closed.

To automatically limit the operation of the valve after a predetermined number of rotations of the blower element have occurred, I have formed the disk 12 with the concentric slot 20 located to register with the valve stem 13 and of a width to receive this valve stem. The thickness of the disk is such that when depressed with its slot

registering with the valve stem, the lever engaging the disk fails to cause it to come into contact with the valve stem to depress the same. As a consequence, the valve remains closed. To rotate the disk 12 with a step-by-step movement for each rotation of the blower element, I have formed upon the disk shoulders formed by the teeth 21 and a cooperating shoulder upon the gear 7 formed by the pin 22, which latter is engageable with the teeth 21 upon each rotation of the gear to advance the disk through an angular movement equal to the distance between the corresponding shoulders of adjacent teeth. Thus it is seen that with this construction, the valve 4 is adapted to be opened as long as the slot 20 of the disk 12 does not register with the valve stem. However, upon continued rotation of the blower element, the disk is rotated until its slot registers with the valve stem, at which time the valve remains closed. In the present instance, the slot 20 is of a length such that three revolutions of the blower element are necessary before the slot passes beyond the valve stem and before the valve can be opened.

In the modified construction of boiler cleaner unit shown in Figures 4, 5 and 6, the blower element 23 is connected to the gooseneck 24 by the usual swivel connection. The gooseneck has at its lower end the valve casing 25 in which the valve 26 is located. 27 is the main valve below the valve 26 for controlling the admission of steam or the like to the gooseneck. This blower element is adapted to be actuated in the same manner as the blower element shown in Figures 1, 2 and 3 as by means of a chain passing over the sheave 28 which is connected to the blower element by means of the pinion 29 and gear 30.

The valve 26 has the valve stem 31 extending upwardly through the casing 25 and adapted to be engaged by the disk 32 yieldably supported above the casing 25 in the same manner as the disk 12 in Figures 1, 2 and 3. This disk 32 is adapted to be axially depressed by means of the pivotal lever 33, the upper end of which is engageable with the cam 34 beside and concentric with the gear 30 and rotatable therewith.

In the present instance, the disk 32 which is adapted to render the valve 26 inoperative, depends upon the admission of steam or the like for subsequently rendering the valve operative. In detail, the disk 32 has the concentric slot 33' so located that it will register with the valve stem 31 and of such a width that the valve stem will freely engage therein. The teeth 34' upon the periphery of the disk 32 are interrupted, one tooth being lacking in the present instance, and this interruption is so located

relative to the slot 33 that when the latter is in registration with the valve stem the driving pin 35 upon the gear 30 passes through this interruption without engaging any tooth so that the disk 32 is no longer rotated. To rotate this disk in order to again operate the valve upon rotation of the blower element, I have provided at one side of the disk and extending transversely of the gear 30, the plunger 36, one end of which slidably engages in the cylinder 37 and the other end of which slidably engages in the bracket 38 secured upon the gooseneck 24. This plunger is provided with the dog 39 pivoted thereon and having its upper end or nose engageable with a tooth 34' upon the disk. The dog is held from rotation in a counter-clockwise direction by means of the transverse pin 40 upon the plunger, but is free to rotate in a clockwise direction to pass the teeth upon the disk when the plunger is being forced to its normal or starting position by the coil spring 41, which surrounds the outer end of the plunger and abuts the bracket 38 and the collar 42 upon the plunger. However, this plunger is not moved to its original or starting position until the main valve 27 is closed and the pressure of the steam or the like above the main valve and in the cylinder is reduced to approximately atmospheric pressure. With the plunger in its normal or starting position and upon opening the main valve, the steam or the like passes through the pipe 43 leading from the valve casing 25 to the cylinder 37, thereby forcing the plunger outwardly and causing the dog 39 to engage a tooth 34' upon the disk 32 to thereby rotate the disk an angular distance equal to that between corresponding sides of adjacent teeth, which brings the first tooth at the side of the interruption into a position where it will be engaged by the driving pin 35 upon operation of the blower element. The operation of the blower element and opening and closing of the valve may now be begun and the control disk will be rotated with a step-by-step movement until its slot again registers with the valve stem, at which time, the valve will remain closed, regardless of whether rotation of the blower element is continued or stopped. However, upon closing and then opening of the main valve, the control disk is again brought into operative position as above described when the same series of operations may be again carried out.

What I claim as my invention is:

1. In a boiler cleaner unit the combination with a blower element movable through a succession of cycles and a valve for controlling the admission of steam or the like to said blower element, of means mounted on the unit for moving said blower element consecutively through said cycles, and means in-

cluding mechanical connections between the blower element operating means and the valve dependent upon the moving of said blower element for opening and closing said valve in each of a predetermined number only of said cycles whereby said valve remains closed during movement of said blower element through one or more cycles after completion of said predetermined number of cycles.

2. In a boiler cleaner, the combination with a rotatable blower element, means for rotating said blower element, and a valve for controlling the admission of steam or the like to said blower element, of means for opening and closing said valve comprising a pivotal lever adapted to be actuated upon rotation of said blower element, and a control member between said lever and valve having an opening registerable with said valve stem.

3. In a boiler cleaner, the combination with a rotatable blower element, means for rotating said blower element and a valve for controlling the admission of steam or the like to said blower element and having a valve stem, of means for controlling the opening and closing of said valve upon rotation of said blower element including a rotatable and axially movable member having a portion engageable with said valve stem and also an apertured portion adapted to register with said valve stem.

4. In a boiler cleaner, the combination with a rotatable blower element, means for rotating said blower element, a valve for controlling the admission of steam or the like to said blower element and having a valve stem, a cam rotatable with said blower element, and a pivotal lever engageable with said cam, of a member for controlling the actuation of said valve, rotatable upon rotation of said blower element and having a portion engageable with said pivotal lever whereby said rotatable member is moved axially and a portion engageable with said valve stem whereby upon axial movement of said member said valve is actuated, said rotatable member also having an opening registerable with said valve stem whereby said member may be moved axially without actuating said valve.

5. In a boiler cleaner, the combination with a rotatable blower element, means for rotating said blower element including a gear, a valve for controlling the admission of steam or the like to said blower element, said valve having a stem, a cam rotatable with said blower element, and a lever engageable with said cam, of a rotatable member for controlling the actuation of said valve located between said lever and valve stem and having a portion engageable with said valve stem for actuating the same and an apertured portion registerable with said valve

stem, said control member being movable axially toward said valve by said lever and being provided with a plurality of shoulders, and a driving projection upon said gear engageable successively with said shoulders to rotate said control member.

6. In a boiler cleaner unit, the combination with a rotatable blower element adapted to discharge a jet of cleaning fluid, a stationary cleaning fluid supply pipe, a valve therein controlling the supply of said fluid to the blower element, and means mounted on said unit to rotate said blower element, of means operated by the first means to operate said valve whereby, upon continued movement of the blower element rotating means, the blower element and valve are moved through successive cycles, and means normally included in the said valve operating means, and automatically acting for preventing the valve operating means from functioning after a predetermined number of successive cycles, whereby said blower element may be moved through one or more additional cycles without effecting an actuation of said valve.

7. In a boiler cleaner unit, the combination with a rotatable blower element adapted to discharge a jet of cleaning fluid, a stationary cleaning fluid supply pipe, a valve therein controlling the supply of said fluid to the blower element and means mounted on said unit to rotate said blower element, of means operated by the first means to operate said valve whereby, upon continued movement of the blower element rotating means, the blower element and valve are moved through successive cycles, and means carried by the blower unit and adapted to co-operate with said valve operating means and automatically acting after a predetermined number of successive cycles thereof for permitting rotation of the blower element through a predetermined number of cycles without actuating the valve.

8. In a boiler cleaner unit, the combination with a rotatable blower element adapted to discharge a jet of cleaning fluid, a stationary cleaning fluid supply pipe, a valve therein controlling the supply of said fluid to the blower element, and means mounted on said unit to rotate said blower element, of means operated by the first means to operate said valve whereby, upon continued movement of the blower element rotating means, the blower element and valve are moved through successive cycles, and means carried by the blower unit and adapted to co-operate with said valve operating means and automatically acting after a predetermined number of successive cycles thereof for permitting rotation of the blower element through a predetermined number of cycles without actuating the valve, said last named means thereafter acting to

again establish an operative connection between the blower element rotating means and the valve.

9. In a boiler cleaner unit, the combination with a blower element, means for moving said element through a succession of cycles, a valve for controlling the flow of cleaning fluid to said element, and a mechanical connection between said blower element and valve normally operable to actuate said valve in each cycle of movement of said blower element of means operable upon movement of said element through a predetermined number of said cycles for rendering said connection inoperative, whereby said element may be moved through one of said cycles without effecting an actuation of said valve.

10. In a boiler cleaner unit, the combination with a blower element, means for moving said element through a succession of cycles, a valve for controlling the flow of cleaning fluid to said element, and a mechanical connection between said blower element and valve normally operable to actuate said valve in each of said cycles of movement of said blower element, of means operable upon movement of said element through a predetermined number of said cycles for rendering said connection inoperative, whereby said element may be moved without effecting an actuation of said valve, said means being also operable upon a further predetermined movement of said blower element to render said connection operative to effect an actuation of said valve from said blower element.

11. In a boiler cleaner unit, the combination with a blower element, means for moving said element, a valve for controlling the flow of cleaning fluid to said element, and a mechanical connection between said blower element and valve for actuating the latter from the former, of means operable upon a predetermined movement of said element for rendering said connection inoperative, whereby said element may be moved without effecting an actuation of said valve, said means including a stem for actuating said valve, a lever actuated upon rotation of the said blower element, a member interposed between the said lever and the valve stem for transmitting the movement of the former to the latter, and means for moving the said member to render the same inoperative.

12. In a boiler cleaner unit, the combination with a rotatable blower element and a valve for controlling the admission of cleaning fluid to said blower element, of means normally operable to open and close said valve during each cycle of rotation of said blower element, and means operable upon rotation of said blower element through a predetermined number of cycles to render said first mentioned means inoperative

whereby said blower element may be rotated through one or more cycles without effecting an actuation of said valve.

13. In a boiler cleaner unit, the combination with a rotatable blower element, a valve for controlling the admission of cleaning fluid to said blower element, and means for rotating said blower element, of a connection between said blower element rotating means and said valve normally operable to open and close said valve during each cycle of rotation of said blower element, and means operable upon rotation of said blower element through a predetermined number of cycles to render said connection inoperative whereby said blower element may be rotated through one or more cycles without effecting an actuation of said valve.

In testimony whereof I affix my signature.

NORMAN L. SNOW.
